Filed Mar. 27, 1967, Ser. No. 6,392

Term of patent 14 years

(Cl. D26—12)

FIG. 1

FIG. 2

FIG. 3

FIG. 4

FIG. 1 is a perspective view of a transmission line support structure, showing my new ornamental design;

FIG. 2 is a front elevational view of the transmission line support structure of FIG. 1;

FIG. 3 is a side elevational view of the transmission line support structure of FIG. 1; and

FIG. 4 is a top plan view of the transmission line support structure of FIG. 1.

The rear elevational view of the transmission line support structure of FIG. 1 is identical with the view of FIG. 2, and the opposite elevational view is identical with the view of FIG. 3. The essential features of my new design reside in the portions shown in solid lines in the drawings.

I claim:

The ornamental design for a transmission line support structure, as shown and described.
